UNITED STATES PATENT OFFICE

2,369,015

PROTECTIVE DEVICE

Guglielmo Camilli, Pittsfield, Mass., assignor to
General Electric Company, a corporation of
New York

Application October 27, 1943, Serial No. 507,849

20 Claims. (Cl. 201—48)

This is a continuation-in-part of my application Serial No. 411,119, filed September 17, 1941.

My invention relates to protective devices, and although not limited thereto it has particular application to protective devices for preventing excessive voltages from being induced in the secondary windings of current transformers upon the secondary circuit being opened.

It has been the practice to provide some arrangement for short circuiting the secondary winding of a current transformer upon the secondary circuit being accidentally opened, since to allow the secondary circuit to be opened with the primary winding connected in a line, will cause very high voltage peaks to be induced in the secondary winding. Such high voltages in the secondary winding may not only injure the meters which are connected thereto but are dangerous to the operator of the meters. An example of a protective device which is designed to prevent such excessive voltages from being induced in the secondary winding of a current transformer upon the secondary winding circuit becoming accidentally opened, is my Patent 2,248,608, issued July 8, 1941, and which is assigned to the same assignee as this present invention. It is also desirable that the protective device be so constructed that there will be no exposed conducting part which may attain any appreciable voltage.

It is therefore an object of my invention to provide a protective device which is not only simple in construction and easy to manufacture, but which will have no exposed conducting parts susceptible of attaining a voltage which may injure anyone who may come in contact with such conducting parts.

Another object of my invention is to provide an improved protective device of the type illustrated in my above mentioned patent.

A further object of my invention is to provide a protective device which will be simple in construction, efficient in operation and have a relatively long life.

Further objects and advantages of my invention will become apparent from the following description referring to the accompanying drawings, and the features of novelty which characterize my invention will be pointed out with particularity in claims annexed to and forming a part of this specification.

In the drawings, Fig. 1 is an end view in partial section of a protective device which is provided with an embodiment of my invention; Fig. 2 is a sectional view taken on line 2—2 of Fig. 1; Fig. 3 is a sectional view taken on line 3—3 of Fig. 2 of a portion of the protective device illustrated in Figs. 1 and 2, showing the construction of a thermostatically operated switch which is employed therein; Fig. 4 diagrammatically illustrates the protective device illustrated in Figs. 60

1—3, as employed in the circuit of a secondary winding of a current transformer; Fig. 5 is an end view in partial section of a modification of the protective device illustrated in Figs. 1 to 4; Fig. 6 is a sectional view taken on line 6—6 of Fig. 5; Fig. 7 is an exploded perspective view of the parts of the protective device of Figs. 5 and 6; Fig. 8 diagrammatically illustrates the protective device of Figs. 5 to 7, as employed in the circuit of a secondary winding of a current transformer; Fig. 9 is a sectional view taken on line 9—9 of Fig. 5.

In the arrangement illustrated in the drawings, I have provided a protective device including at least a pair of electrodes and a resistance material separating or between the electrodes, the latter being adapted to be connected across an electrical apparatus which is to be protected, such as the secondary winding of a current transformer. It is to be understood, however, that my protective device has application to any other apparatus which should be protected from abnormal high voltages. The protective device is a relatively high impedance for normal voltages in the secondary winding or other electrical apparatus to which the protective device is connected, but it provides a relatively low impedance and will short circuit the secondary winding upon a predetermined abnormal voltage being induced in the secondary winding. The resistance material is susceptible of becoming overheated upon a current flowing therethrough, and so I provide an improved construction, including a thermostatically operated switch for short circuiting the electrodes and therefore the resistance material, when the latter becomes overheated. One of the electrodes, in the construction shown in Figs. 1 to 4, is provided with a recessed portion providing a chamber facing the resistance material, for accommodating the thermal responsive device so that the latter may be responsive to heat from the resistance material. The other electrode is in the form of a cup shaped member so as to substantially enclose the first mentioned electrode and resistance material. I further find it extremely desirable to provide an arrangement for grounding the cup shaped electrode, the latter being susceptible of being touched by an operator, so that the operator will not be injured if he accidentally touches this exposed conducting part.

Referring more particularly to Figs. 1 and 2 of the drawings, I have provided a protective device which includes an inner or first electrode 10 and an outer second electrode 11. As is seen more clearly in Fig. 2, the pair of electrodes 10 and 11 are provided with faces which have substantially parallel adjacent portions 12 and 13 respectively. A resistance material 14 separates or is held between the substantially parallel face

portions 12 and 13 of the electrodes. This resistance material may take any suitable shape, and it will be seen from Fig. 2, that a plate shape is a convenient form, and the thickness thereof may be of any suitable value, depending upon the characteristics which are desired and the operating voltage and current of the device which is to be protected. Furthermore, the resistance material 14 may be composed of any suitable material, such as that having a non-linear resistance-ampere characteristic. I have found that a suitable material having such non-linear characteristics is that material having a hyperbolic resistance-current characteristic of the type described in Patent 1,822,742 McEachron, this patent being assigned to the same assignee as this present invention.

In order to provide an improved arrangement for short circuiting the resistance material 14 so as to prevent it from becoming overheated when it operates to short circuit the secondary winding of the current transformer or other electrical apparatus which is being protected, I provide an improved structure which includes a suitable thermal responsive device such as a bimetallic element 15 and a suitable switch having contacts 16 and 17 which are adapted to be actuated by the temperature responsive device 15, upon the latter being heated in any suitable manner as a function of the temperature of the resistance material such as by heat from the resistance material 14. The switch which is adapted to be actuated by the temperature responsive device may be of any suitable construction and in the arrangement illustrated, as will be seen clearly in Fig. 3, the contact 16 is mechanically carried by the end of the bimetallic element 15 and electrically connected thereto and the contact 17 is mechanically supported by and electrically insulated from the electrode 10 by an arrangement having a conducting portion and an insulating portion. This latter arrangement includes a conducting member 18 which is insulated from the electrode 10 by insulating washers 19 and 19'. In order to control the temperature at which the temperature responsive device will cause the switch contacts 16 and 17 to open and close I provide an adjustment arrangement including a screw 20, which has an end 21 connected to the bimetallic element 15. The end 21 is insulated from the bimetallic element 15 by insulating washers 22 and it will be seen that when a nut 23 which cooperates with the bolt 20 and a face of the electrode 10 is loosened, the bolt 20 may be rotated, thus varying the distance between the contacts 16 and 17 and thereby controlling the distance through which the end of the bimetallic element 15 must traverse before it may open and close the contacts 16 and 17.

In order to not only provide a convenient supporting arrangement for the bimetallic element 15 but so that it may be thermally associated with the resistance material, the electrode 10 is provided, as will be seen in Figs. 2 and 3, with a recessed portion 24 of a suitable shape so that it may accommodate the temperature responsive device and switch contacts. The recessed portion 24 may be formed in any suitable manner such as pressing out the portion 24 when the electrode 10 is being fabricated. It will therefore be seen that the recessed portion 24 forms a chamber 25 which opens toward the resistance material 14 so that the heat may pass quickly from the resistance material to the bimetallic

element 15 within the chamber 25. It will further be seen that a shoulder portion 26 is provided relatively close to the resistance material 14 upon which an end of the bimetallic element 15 may be supported so that this element may be supported relatively close to the resistance material 14 and thereby further improve the heat transfer characteristics between the resistance material 14 and the bimetallic element 15. It is to be understood, of course, that the recessed portion 24 may take any other suitable shape so as to accommodate the bimetallic element in order that it may be thermally associated with the resistance material 14.

In order to provide a convenient arrangement for electrically connecting the electrodes 10 and 11 to the secondary winding of the current transformer or other electrical apparatus which is to be protected, I provide terminals 27 and 28, which are connected to the electrodes 10 and 11 respectively. The terminal 27 has a flared end portion 27' which may be connected to the terminal 10 in any suitable manner, such as by brazing. Suitable nuts 29 are provided on the terminal 27 for tightly securing a connector 30 of a conductor 31 to the terminal 27. The terminal 28 is similarly provided with suitable nuts 32 for connecting a terminal 33 of a conductor 34 to the terminal 28. It will be further seen in Fig. 2 that the electrode 10 and resistance material 14 are provided with holes or bores 35 and 36 in substantial registry for accommodating a portion of the terminal 28. An end 37 of the terminal 28 may be electrically connected to the electrode 13 in any suitable manner, such as by brazing, the end 37 being electrically insulated from the resistance material 14 and surfaces of the bores 35 and 36 by an insulating ring 38. The terminal 28 is also insulated from the terminal 10 by a portion of the ring and by the air space between the surface of the bore 35 and the terminals 28.

Since the thermostatically operated switch with contacts 16 and 17 are, upon closure thereof, to short circuit the electrodes 10 and 11, an improved arrangement is provided for electrically connecting the contacts 16 and 17 to the electrodes 10 and 11, respectively. The contact 16 is electrically connected to the electrode 10 through the bimetallic element 15 and a rivet 39, which also provides for the mechanical supporting arrangement for the bimetallic element 15. The contact 17 is connected to the electrode 11 through the rivet 18, which provides the supporting arrangement for the contact 17. This rivet is in turn connected to the terminal 28 by a conducting strap 40, which, as will be seen in the drawings, has one end connected to the rivet 18 and an opposite end 42 connected to the terminal 28. The latter connection is made through metal washers 43 and 44 and the adjacent nut 32. The metal washer 43 is in turn insulated from the electrode 10 by an insulating washer 45.

Operation of my protective device is as follows: As has already been stated, my protective device may be connected across the terminals of any suitable device such as the secondary winding of a current transformer in order to prevent an abnormal voltage from being induced therein. Referring to Fig. 4, it will be seen that there is schematically illustrated a current transformer having a primary winding 46, which is adapted to be connected in a line and a secondary winding 47, which is connected to the terminals 27 and 28 through the conductors 31 and 34. There is also

schematically shown a meter 48 which is adapted to be connected across the secondary winding 47 of the transformer. Let us assume, therefore, that one of the lines which connects the meter 48 to the secondary winding 47 has become open circuited. Such is very liable to happen since the meters are removably connected to the secondary winding 47; as it may be necessary to connect and remove the meter several times during a metering operation. It will be understood that during a normal voltage being induced in the secondary winding, that substantially no current will flow through the protective device, as the resistance material 14 has such characteristics that when a predetermined low voltage is impressed across it, it will be substantially an insulator. The characteristics of the material 14 may be so designed, however, that upon a predetermined abnormal voltage being impressed across the terminals 27, 28, that is, when the secondary winding circuit is opened, the resistance of the material 14 will be substantially lowered thereby forming a relatively low resistance path for the current through the protective device. It has been found, however, that it is necessary to in turn short circuit the resistance material 14 under these conditions to prevent it from becoming overheated and damaging the protective device. Thus, upon a predetermined temperature being present in the resistance material 14, the temperature responsive device 15 will actuate the contacts 16 and 17 to a closed position and thereby short circuit the resistance material 14. It will also be seen therefore that the contacts 16 and 17 also provide a low resistance path for the current flowing in the secondary winding circuit, so that high voltage will also be prevented from being induced in the secondary winding 47. The temperature responsive device 15 may be designed to have such characteristics that it will in turn open its contacts 16 and 17 upon the temperature of the resistance material 14 having dropped to a predetermined value. The protective device may therefore operate in this manner until the operator notices the open circuit and rectifies the difficulty.

It will be seen from Fig. 4 that the line 34, which connects through the terminal 28 to the electrode 11 is grounded at 49, so that the electrode 11 will be maintained at substantially ground potential at all times. Since the electrode 11 substantially encloses the electrode 10 and resistance material 14, the chances of the operator, upon accidentally touching the protective device coming in contact with conducting material which may be at high voltage, is reduced to a minimum. Furthermore, an insulating support 50 may be made of any suitable shape and size so as to prevent the operator from touching the end of the terminal 27. It will be apparent that the protective device may be supported on a base through the supporting member 50 so that the electrode 10 will be adjacent the base and thereby reduce to a minimum the possibility of operator accidentally touching the electrode 10. The support 50 is shown as being attached to the unitary assembly, including the pair of electrodes and resistance materials, by screws 51.

In view of the foregoing, it will be seen that I have provided an improved protective device which is simple in construction, economical to manufacture and efficient in operation. Furthermore, the shape of the exposed electrode is such as to substantially enclose the conducting members which may attain a relatively high volt-

age, the exposed conducting surface being adapted at all times to be connected to ground potential.

On sheet 2 of the drawings I have illustrated a modified protective device which is relatively rugged in construction and which has a plurality of resistance disks so that it may be employed to protect an electric apparatus of relatively high capacity. The construction includes, as will be seen in Figs. 5 and 6, a pair of resistance members 60 and 61 which may be made of any suitable material such as the same material mentioned above in connection with disk 14. A first pair of electrodes 62 and 63 are provided on either side of the disk 60 and a second pair of electrodes 64 and 65 are provided on either side of the second disk 61.

In order to provide an arrangement for short circuiting the resistance disks 60 and 61 so as to prevent them from becoming overheated during operation of the device, I may provide any suitable thermal responsive device or control device which is operative in response to the current flowing through the resistance disk or in response to a function of the temperature of the resistance disk. In the construction as is illustrated in Fig. 6 the thermal responsive device includes a bimetallic member 66, one end of which is supported through a conductor 67. So as to provide a convenient way of spacing the two pairs of disks and cooperating electrodes as well as mounting the thermal responsive device I provide a member 68 of suitable material such as a molded insulated product which has a cavity 69, as will be seen more clearly in the exploded view of Fig. 7 in which the thermal responsive device is supported. One end of the conducting member 67, as will be seen in Fig. 6, is supported on the wall 70 of the insulating member through a rivet 71. Upon the outer end of the bimetallic member 66 is carried a contact 72 which cooperates with a relatively stationary contact 73 which is supported on the wall member 74 of the insulating spacer 68.

In order to electrically connect the protective device including the resistance plates across a suitable electrical apparatus to be protected, such as the secondary of a current transformer, there is provided a relatively high voltage terminal 75 and a relatively low voltage terminal 76. As will be seen in the diagrammatic representation in Fig. 8, the terminal 75 is adapted to be connected to the secondary of a current transformer 77 through a conductor 78 while the terminal 76 is adapted to be connected to the opposite end of the current transformer secondaries through a conductor 79. It is to be understood that the terminal 79 may be grounded if desired as is indicated at 80. The terminal 75 is in the form of a hollow conductor through which extends a wire 81, the inner end of which is soldered to the conducting strap 82 as illustrated particularly in Fig. 7, the outer end being soldered to the outer end of the bushing as is illustrated at 83.

In order to provide a construction which is relatively shock proof and which also has a casing which may be connected to ground potential, it will be seen that the lower electrode 65 is provided with an integral side wall 85 so as to provide a cup-shaped member. Furthermore, the insulating spacer 68 is provided with a downwardly extending lip 86 for spacing the disk 61 from the side walls 85 and an upwardly extending lip 87 for spacing the disk 60 from the side walls 85 of the casing. Also as will be seen particularly in Fig. 6, the upper edge of the side walls 85 are

spun over as is indicated at 88 and contact the adjacent electrode 62 so as to relatively tightly support the various parts of the protective device inside the enclosing casing including the lower electrode 65, the integral side wall and the upper electrode 62. A metallic plate member 90 may be provided which is attached to the lower electrode 65 in any suitable manner such as by welding so as to provide a relatively rugged supporting foot for the electrical device.

In order to provide an arrangement for insulating the relatively high voltage lead from the surrounding casing 85 I provide an opening 91 in the casing through which extends an insulating member 92 which in turn has an opening through which extends the conducting member 75. Integral with the insulating member 92 is provided an insulating plate member 93 for cooperating with the inner face of the wall 85, and a suitable washer 94 of insulating material is provided which surrounds the insulating member 92 and prevents the washers and nuts 95 between which the lead from the wire 78 may be attached, from touching the casing 85.

So as to provide an arrangement for heating the bimetallic strip in response to or as a function of the current or temperature of the resistance disks, I provide a heater 100 adjacent the bimetallic disk which has one end 101 electrically connected to the conducting strap 67 which in turn connects with the high voltage lead 75. The other end of the heater 100 connects with a rivet 102 which will be seen in Fig. 5, and in the detail of Fig. 9. The rivet is in turn supported on a wall 103 of the insulating spacer 68 with a pair of spring members 104 and 105 supported on opposite sides of the wall 103 and electrically connected to the rivet 102. It will be seen that as the parts are assembled in the manner shown in Fig. 6, the spring 104 will contact the adjacent electrode 63 while the spring 105 will contact the adjacent electrode 64. Thus the high voltage connection may be traced from the high voltage terminal 75 through the conductor 81 to the bimetallic element 66 and through the heater 80 and springs 104, 105 to the inner electrodes 63 and 64.

In order to provide a relatively low voltage connection between the terminal 76 and the outer shell to the contact 73, a screw 109 is provided which contacts with the bottom of the electrode 65, as will be seen in Fig. 2, and screws into a nipple of suitable conducting material 110 on the end of which is supported a conducting strap 111, the lower end of the strap 111 being in turn connected to the contact 73. Since the integral side walls 85 connect through the spun-over ends 87 to the upper electrode 62, it will be seen that both of these electrodes are connected to the terminal 76 which in turn connects with the low voltage side of the secondary winding through the conductor 79. It will be seen that the disk 61 has an internal base 115 and the electrode above 116 through which the member 110 extends so that there is no electrical connection.

Operation of my improved protective device is shown in Figs. 5 through 9 and is as follows: With the protective device connected across the secondary winding 71 of a current transformer which is in turn connected to an ammeter as indicated by the numeral 115 in Fig. 8, so long as normal voltage is impressed across terminals 75 and 76 of the protective device substantially no current will flow through the protective device. However, when a relatively high voltage is im-

pressed across the terminals occasioned, as by an open circuit in the secondary circuit, current flow may be traced in the diagrammatic view of Fig. 8 through the high voltage terminal 75, the conductor 81, and through the heater 100 to the conducting straps 104 and 105. The straps are, of course, connected to the electrodes 63 and 64. Current may then flow through the resistor disks 60 and 61 to the electrodes 62 and 65. The circuit may then be traced out the low voltage terminal 76 and from the conducting electrode 79 to the opposite side of the secondary winding and also to ground through member 80. It will, of course, be understood that the heater device may be calibrated in relation to the thermostatic device such that the contacts 72 and 73 will be made to close when the resistor disks 60 and 61 have obtained any suitable temperature. Thus it may be said that the thermal responsive device is operative in response to the function of the temperature of the resistor disks. Upon closure of the contacts 72 and 73 the disks will be short circuited so that the current may flow, as will be seen in Fig. 8, from the conducting strap 81 through the bimetallic strip 67 through the contacts 72 and 73 and directly to the low voltage terminal 76. With the current removed from the heater element 100 it will be understood that after a suitable time, depending upon the characteristics of the device, the contacts will again open thus causing current to again flow through the resistor disks. This operation will, of course, continue until the operator recloses the secondary of the transformer through the meters and leads.

In the construction as is shown in Figs. 5 through 9 it will be seen that I have provided a device which has an enclosing housing which is not only adapted to be connected to ground but I have also provided a relatively rugged construction which may be considered shock proof. It is to be understood that the high voltage terminal 75 may be turned so that it projects away from the normal position of the operator, or if desired an insulating cap member 112 may be provided over the bushing so as to protect the operator from coming in contact with this high voltage lead, the cap, of course, having an opening through which the insulated conductor 79 may project.

Modifications of the particular arrangements which I have disclosed embodying my invention will occur to those skilled in the art, so I do not desire my invention to be limited to the particular arrangements set forth and I intend in the appended claims to cover all modifications which do not depart from the spirit and scope of my invention.

What I claim as new and desire to secure by Letters Patent of the United States is:

1. A protective device including a pair of electrodes adapted to be connected to an electrical apparatus to be protected, a resistance material connected between said electrodes, a temperature responsive device thermally associated with said resistance material, and a switch having a pair of contacts connected across said electrodes, said temperature responsive device being adapted to actuate said contacts upon being heated by heat from said resistance material, one of said electrodes being cup shaped so as to substantially enclose said other electrode and said resistance material.

2. A protective device including a pair of electrodes adapted to be connected to an electrical apparatus to be protected, a resistance material

connected between said electrodes, a temperature responsive device thermally associated with said resistance material, a switch having a pair of contacts connected across said electrodes, said temperature responsive device being adapted to actuate said contacts upon being heated by heat from said resistance material, one of said electrodes being cup shaped so as to substantially enclose said other electrode and said resistance material, and means for grounding said cup shaped electrode.

3. A protective device including a pair of electrodes having substantially flat parallel adjacent surfaces, a plate of resistance material held between said adjacent surfaces of said electrodes, a temperature responsive device thermally associated with said resistance material, a switch having a pair of contacts connected across said electrodes, said temperature device being adapted to actuate said contacts upon being heated by heat from said resistance material, one of said electrodes being cup shaped so as to substantially enclose said other electrode and said resistance material, said cup shaped electrode being adapted to be grounded.

4. A protective device including a pair of electrodes adapted to be connected to an electrical apparatus to be protected, said electrodes having adjacent faces with substantially flat parallel portions, a resistance material between said adjacent faces of said electrodes, one of said electrodes having a recessed portion, a temperature responsive device within said recessed portion so that it will be affected by heat from said resistance material, a switch having a pair of contacts connected across said electrodes, said temperature responsive device being adapted to close said contacts upon said resistance material becoming over-heated so as to short circuit said resistance material.

5. A protective device including a pair of electrodes having adjacent faces with substantially flat parallel portions, a plate of resistance material held between said adjacent faces of said electrodes, a switch having contacts connected across said electrodes, a temperature responsive device being adapted to actuate said switch upon said temperature responsive device becoming heated, one of said electrodes having a recessed portion defining a chamber facing said resistance material, and means for supporting said temperature responsive device within said chamber so that it will be affected by heat from said resistance material.

6. A protective device including a pair of electrodes having adjacent faces with substantially flat parallel portions, a plate of resistance material held between said adjacent faces of said electrodes, a temperature responsive device being adapted to actuate said switch upon said temperature responsive device becoming heated, one of said electrodes having a recessed portion defining a chamber facing said resistance material, and means for supporting said temperature responsive device within said chamber so that it will be affected by heat from said resistance material, said other electrode being cup shaped so as to substantially enclose said one electrode and said resistance material.

7. A protective device including a first and a second electrode having adjacent faces with substantially flat parallel portions, a plate of resistance material held between said adjacent faces of said electrodes, said first electrode and said plate of resistance material having bores

in substantial registry, a terminal extending into said bores and being electrically connected to said second electrode, means for insulating said terminal from said plate of resistance material and said first electrode, a temperature responsive device thermally associated with said resistance material and having a pair of contacts adapted to be actuated upon said temperature device becoming heated, and means for connecting one of said contacts to said terminal and said other of said contacts to said first electrode so that said electrodes will be short circuited upon said contacts being closed by said temperature responsive device.

15 8. A protective device including a first and a second electrode having adjacent faces with substantially flat parallel portions, a plate of resistance material held between said adjacent faces of said electrodes, said first electrode and said plate of resistance material having bores in substantial registry, a terminal extending into said bores and being electrically connected to said second electrode, means for insulating said terminal from said plate of resistance material and said first electrode, a temperature responsive device having a pair of contacts adapted to be actuated by said temperature responsive device, said first electrode having a recessed portion defining a chamber facing said resistance material, means for supporting said temperature responsive device within said chamber so that it will be affected by heat from said resistance material and for connecting one of said contacts to said first electrode, and means including said terminal for connecting said other contact to said second electrode.

40 9. A protective device including a first and a second electrode having adjacent faces with substantially flat parallel portions, a plate of resistance material held between said adjacent faces of said electrodes, said first electrode and said plate of resistance material having bores in substantial registry, a terminal extending into said bores and being electrically connected to said second electrode, means for insulating said terminal from said plate of resistance material and said first electrode, a temperature responsive device having a pair of contacts adapted to be actuated upon said temperature responsive device becoming heated, said first electrode having a recessed portion defining a chamber facing said resistance material, means for supporting said temperature responsive device within said chamber so that it will be affected by heat from said resistance material and for connecting one of said contacts to said first electrode, means including conducting and insulating portions for supporting and insulating said other contact on said first electrode, and a conductor for connecting said terminal with said conducting portion of said last mentioned means.

45 10. A protective device including a first and a second electrode having adjacent faces with substantially flat parallel portions, a plate of resistance material held between said adjacent faces of said electrodes, said first electrode and said plate of resistance material having bores in substantial registry, a terminal extending into said bores and being electrically connected to said second electrode, means for insulating said terminal from said plate of resistance material and said first electrode, a temperature responsive device having a pair of contacts adapted to be actuated upon said temperature responsive device be-

coming heated, said first electrode having a recessed portion defining a chamber facing said resistance material, means for supporting said temperature responsive device within said chamber so that it will be affected by heat from said resistance material and for connecting one of said contacts to said first electrode, and means including said terminal for connecting said other contact to said second electrode, said second electrode being cup shaped so as to substantially enclose said first electrode and said resistance material, said second electrode being adapted to be grounded.

11. A protective device including a pair of electrodes adapted to be connected to an electrical apparatus to be protected, a resistance material connected between said electrodes, a temperature responsive device having contacts connected to said electrodes so that said resistance material may be short circuited by the closing of said contacts, said temperature responsive device being adapted to actuate said contacts in response to current flow through said resistance material, one of said electrodes being cup shaped so as to substantially enclose said other electrode and said resistance material.

12. A protective device including a pair of electrodes adapted to be connected to an electrical apparatus to be protected, a disc-shaped resistance material connected between said electrodes, a temperature responsive device having contacts connected to said electrodes so that said resistance material may be short circuited by the closing of said contacts, said temperature responsive device being adapted to actuate said contacts in response to the heating effect of current flow through said resistance material, and means for grounding one of said electrodes.

13. A protective device including a pair of electrodes having substantially flat parallel adjacent surfaces, a plate of resistance material between said adjacent surfaces of said electrodes, a temperature responsive device adjacent one of said electrodes, said temperature responsive device having a pair of contacts connected to said electrodes and operative upon being heated as a function of the temperature of said resistance plate to short circuit said plate, one of said electrodes being cup shaped so as to substantially enclose said other electrode and said resistance plate.

14. A protective device including a pair of electrodes adapted to be connected to an electrical apparatus to be protected, a resistance material connected between said electrodes, a temperature responsive device having a pair of contacts connected to said electrodes for short circuiting said resistance material upon closure of said contacts, heater means adjacent said temperature responsive device, means for connecting said heater device to said electrodes so that said temperature responsive device will be heated as a function of the current flow through said resistance material, one of said electrodes being cup shaped so as to substantially enclose said other electrode and said resistance material.

15. A protective device including two pairs of spaced electrodes, resistance material connected between each of said pairs of electrodes, a thermal responsive device having a pair of contacts, means including insulating means for supporting said thermal responsive device between one electrode of one pair and another electrode of said other pair, means for connect-

ing one electrode of each pair and the other electrode of each pair to an electrical apparatus to be protected, means for connecting said contacts to said electrodes so that closing of said contacts will short circuit said resistance material, means for heating said thermal responsive device as a function of the temperature of said resistance material during operation of said device, and means including one of said electrodes of one pair and another of said electrodes of the other of said pairs acting as an enclosing housing for the other parts of said device.

16. A protective device including a first pair of electrodes, a plate of resistance material connected between said electrodes, a second pair of electrodes, a second plate of resistance material connected between said second pair of electrodes, a thermal responsive device having a pair of contacts, means including insulating means for supporting said thermal responsive device between said first and said second pair of electrodes, heater means adjacent said thermal responsive device, a pair of terminals, means for connecting one of the electrodes of each of said pairs and one contact to one terminal, means for connecting the other of said electrodes of each of said pairs and said other contact to said other terminal, and means for operating said thermal responsive device in response to a function of the temperature of said resistance plates during operation of said device.

17. A protective device including a first pair of electrodes, a plate of resistance material connected between said electrodes, a second pair of electrodes, a second plate of resistance material connected between said second pair of electrodes, a thermal responsive device having a pair of contacts, means including insulating means for supporting said thermal responsive device between said first and said second pair of electrodes, heater means adjacent said thermal responsive device, a pair of terminals, means for connecting one of the electrodes of each of said pairs and one contact to one terminal, means for connecting the other of said electrodes of each of said pairs and said other contact to said other terminal, and heater means connected with said electrodes so that said thermal responsive device may be heated as a function of the temperature of said resistance disks during operation of said device.

18. A protective device including a first pair of electrodes, a plate of resistance material connected between said electrodes, a second pair of electrodes, a second plate of resistance material connected between said second pair of electrodes, a thermal responsive device having a pair of contacts, means including insulating means for supporting said thermal responsive device between said first and said second pair of electrodes, heater means adjacent said thermal responsive device, a pair of terminals, means for connecting one of the electrodes of each of said pairs and one contact to one terminal, means for connecting the other of said electrodes of each of said pairs and said other contact to said other terminal, and means for operating said thermal responsive device in response to a function of the temperature of said resistance plates during operation of said device, one of said electrodes of one of said pairs having a cup shape and one of said electrodes of said other pair being a closure for said cup shaped electrodes so that said last two mentioned electrodes provide an en-

closing housing for the remaining parts of said device.

19. A protective device including a plurality of spaced plates of resistance material with plate electrodes on opposite sides thereof, insulating means spacing adjacent electrodes of adjacent plates of resistance material, control means supported by said insulating means for short circuiting said resistance plates in response to over-load conditions, one of said electrodes having an integral side providing a tubular shaped member, said side having an integral lip cooperating with another of said electrodes providing a relatively tightly assemblage of parts within said enclosing electrodes.

20. A protective device including a pair of elec-

trodes adapted to be connected to an electrical apparatus to be protected, a disc-shaped resistance material connected between said electrodes, a temperature responsive device having contacts connected to said electrodes so that said resistance material may be short circuited by the closing of said contacts, said temperature responsive device being adapted to actuate said contacts in response to current flow through said resistance material, and means including one of said electrodes providing a substantially enclosing housing for said other electrode and said resistance material, said housing being adapted to be grounded.
